(57) **CLAIM**

I claim the ornamental design for a pet toy, as shown and described.

DESCRIPTION

FIG. 1 is a perspective of a pet toy, showing my new design. FIG. 2 is a top plan view of the pet toy of FIG. 1, the bottom plan being identical thereto; and, FIG. 3 is a side view of the pet toy of FIG. 1, the other side, front and rear views being identical thereto.

1 Claim, 2 Drawing Sheets

FIG. 1

FIG. 2**FIG. 3**
